(57) **CLAIM**

The ornamental design for a protective garment, as shown and described.

DESCRIPTION

FIG. 1 is a front view illustrating my design for a protective garment;

FIG. 2 is a rear view thereof;

FIG. 3 is a rear view of one embodiment thereof with surface treatment presented in broken lines;

FIG. 4 is a left side view thereof, the right side view being a mirror image of the left side view;

FIG. 5 is a bottom view thereof; and,

FIG. 6 is a rear perspective view thereof, shown in an environment of use.

The broken lines in the figures represent portions of the article which form no part of the claim.

1 Claim, 4 Drawing Sheets
